ELECTRODE RELEASE FOR ARC LAMPS

Fielding C. Coates, Los Angeles, Calif., assignor
to Mole-Richardson Co., Los Angeles, Calif., a
limited partnership of California

Application August 27, 1938, Serial No. 227,142

12 Claims. (Cl. 176—119)

My invention relates to an improved electrode release for arc lamps and has particular utility when employed with arc lamps of the type in which the electrode is continuously rotated and advanced during operation.

In arc lamps of the type for which the subject matter of this invention is adapted for use, either one or both electrodes are continuously rotated during the operation of the lamp. An example 10 of this type of arc lamp is disclosed in the United States patent to Elmer C. Richardson, No. 2,060,347.

The principal objection to lamps of this type has been the difficulty in removing spent electrodes and replacing them with new ones. This difficulty has been due to the fact that no means was available to relieve the high pressure exerted on the electrode by the electrode feeding wheels or gears.

20 Release mechanisms have been devised to free the electrode, but none have thus far provided either or both manual or automatic means for effecting the positive disengagement of the release and the re-engagement of the feeding 25 means whenever the lamp is started up after a change of electrodes. A disadvantage in the present types of releases lies in the tendency for the release mechanism to become locked in the released position.

30 It is therefore a primary object of my invention to provide a simple and expedient means for releasing an electrode to permit ready replacement thereof, wherein said releasing means may be positively operated to a disengaged position either manually or, preferably, automatically when the arc lamp is put into operation.

It is an additional object of my invention to provide a means for releasing the electrode which will automatically effect the re-engagement of 40 the feeding means whenever the lamp is replaced in operation, even though the workman should inadvertently fail to return the releasing mechanism to the "off" position.

It is also an object of my invention to provide 45 a release mechanism of the character set forth in which the force tending to return said mechanism to the non-released position is at its greatest when in a position to release the electrode.

Other objects and advantages of my invention 50 will be apparent from a study of the following specifications read in connection with the accompanying drawings, wherein

Fig. 1 is a longitudinal section illustrating the feeding and electrode releasing mechanism employed with one of the electrodes of a lamp of

the type described in the United States patent to Richardson, No. 2,060,347, issued November 10, 1936.

Fig. 2 is a transverse section taken along the line II—II of Fig. 1 and illustrating the relationship between the electrode feeding gears and the mechanism for disengaging these gears from the electrode;

Fig. 3 is a longitudinal section similar to Fig. 1 but showing the release mechanism of my invention in the released position and with certain of the feeding mechanism deleted;

Fig. 4 is a perspective view illustrating one form of the release member of my invention;

Fig. 5 is a fragmentary plan view, partly in section, taken as indicated by the line V—V of Fig. 3;

Fig. 6 is a longitudinal section illustrating the feeding mechanism only, and showing an alternative type of release mechanism;

Fig. 7 is a transverse section taken along the line VII—VII of Fig. 6 showing additional details of the mechanism shown in Fig. 6;

Fig. 8 is a longitudinal section similar to Fig. 6 but illustrating a third form of release mechanism;

Fig. 9 is a transverse section taken along the line IX—IX of Fig. 8;

Fig. 10 is a longitudinal section similar to Fig. 8 but illustrating an alternative arrangement of the parts shown in Fig. 8;

Fig. 11 is a longitudinal section showing a release mechanism control which may be substituted for the control shown in Figs. 1, 3 and 5;

Fig. 12 is a transverse section taken along the line XIII—XII of Fig. 11; and

Fig. 13 is a plan view showing the control mechanism illustrated in Fig. 11.

The electrode feeding means to which the release device of my invention is applied is illustrated in Fig. 1 (it being understood that Fig. 1 illustrates only that portion of the type of arc lamp previously referred to which includes the feeding mechanism for one of the plurality of electrodes employed, the other electrode, mechanism associated therewith, and lamp housing being deleted) as including an electrode 15 carried in a gear housing 16 which encloses the driving and feeding mechanism therefor.

Power for rotating and feeding the electrode 50 15 is supplied through a suitable shaft 17 to which is affixed a bevel gear 18 arranged to mesh with another bevel gear 19 suitably attached to an electrode carrier or sleeve 20 in which the electrode 15 is inserted. The sleeve 20 is suit-

ably journaled for rotation as by means of ball bearings 21 and 22 interposed between the sleeve 20 and the housing 16.

A spur gear 23 is suitably attached as by a key 23a to the rotatable sleeve 20 and is arranged to engage supplementary gearing (not shown), which gearing also engages another spur gear 24. The spur gear 24 is rotatably supported by the rotatable sleeve 20 so that it may rotate independently of the sleeve 20 upon the exterior thereof.

The spur gear 24 has teeth 25 formed on the forward face thereof, which teeth are arranged in a spiral or scroll form. A pair of electrode feeding wheels 26 and 27 are provided which may be formed with gear teeth arranged to mesh with the teeth 25 of the scroll gear and to also engage the sides of the electrode 15.

In order to properly locate and support the electrode feeding wheels 26 and 27, a face plate 28 is provided which is securely attached in any suitable manner to the rotatable sleeve 20 and has provided thereon bearing brackets through which suitable shafts or axles 32 and 33 are passed. The shafts 32 and 33 are employed as axle members for the feeding wheels 26 and 27.

Bearing brackets 30 and 31 are slotted as indicated at 34 and 35 so that the axles 32 and 33 may move inwardly and outwardly with respect to the electrode 15. Resilient means (preferably tension springs as 36 and 37) are coupled to the shafts 32 and 33 in the manner illustrated in Fig. 2 so as to urge the wheels 26 and 27 inwardly to forcibly engage the electrode 15.

In operation, the sleeve 20 is rotated by power supplied through the shaft 17 in such direction as to cause the electrode 15 to rotate in the direction indicated in Fig. 1 by an arrow 38. The gearing interposed between the spur gears 23 and 24 and the direction in which the spiral teeth 25 are developed is so arranged as to cause the electrode feeding wheels 26 and 27 to rotate in opposite directions and feed the electrode 15 forwardly as indicated by arrow 39 in Fig. 1.

A heat absorber and radiator 40 is suitably secured to the housing 16 and arranged to shield the mechanism previously described from the flame of the arc so as to prevent raising the temperature of the aforementioned working parts to an undesirable value.

Although the foregoing description is directed to a common form of feeding and driving mechanism for the electrode of an arc lamp, it is included herein to facilitate the understanding of the way in which the release mechanism of my invention operates. While I have illustrated the release mechanism of my invention as being applied to the type of lamp mechanism just described, it is to be understood that this mechanism may also be readily applied to other types of electrode rotating and feeding devices.

It will be readily seen from the foregoing that in order to remove the electrode 15 from the sleeve 20 through which it is inserted, it is necessary to disengage the feeding wheels 26 and 27 and that such disengagement must be accomplished by overcoming the force of the tension springs 36 and 37 urging said wheels toward the electrode 15. It is common practice to make the springs 36 and 37 very strong in order that the electrode feeding wheels 26 and 27 may positively engage the electrode 15. In view of the strength of the springs 36 and 37 it is a difficult task to disengage the feeding gears from the electrode 15 unless a control means for so doing is provided.

The control means for accomplishing the above includes an internal sleeve 45 which is interposed between the electrode 15 and the driving sleeve 20 and arranged to slide freely therebetween. The internal sleeve 45 is extended forwardly past the electrode feeding wheels 26 and 27 and terminates in a release member 46 suitably attached thereto. The sleeve 45 is provided with slots 47 and 48 (Fig. 2) through which the electrode feeding wheels 26 and 27 pass so as to engage the electrode 15. 10

The release member 46 is illustrated in Fig. 4 and includes a transverse portion 50 in which is provided a suitable opening 51 for attachment to the sleeve 45. Extending on either side of the electrode 15 and attached to the transverse portion 50 is a pair of longitudinal portions 52 and 53. The longitudinal portions 52 and 53 are spaced apart a sufficient distance to straddle or pass over the bearing bracket structures 30 and 31. 20

I provide on each of the longitudinal portions 52 and 53 a pair of tapered surfaces 54a—54b and 54c—54d. In order that these tapered surfaces may operate as a wedging means to stretch the tension springs 36 and 37 and release the electrode feeding wheels 26 and 27 from the electrode 15, I provide suitable rollers 55a, 55b, 55c, 55d rotatably supported upon the shafts 32 and 33, rollers 55a and 55b being associated with the shaft 32 30 and similar rollers 55c and 55d being associated with the shaft 33. 30

In order that the aforementioned rollers may be held in the proper position longitudinally on the pins 32 and 33, I provide grooves 56a, 56b, 56c, 56d in the face plate 28 and extending at right angles to the shafts 32 and 33. The rollers are preferably of such diameter as to extend into the grooves associated therewith, the grooves thus operating to prevent the rollers from shifting longitudinally along the shafts 32 and 33. The rollers 55a and 55b and the complimentary rollers 55c and 55d are spaced apart by the grooves 56a, 56b, 56c, 56d the proper distance to be engaged by the tapered surfaces provided on the longitudinal members 52 and 53 of the release member 46. 40

Reference to Figs. 1 and 4 will show that movement of the sleeve 45 to the left, as shown in Fig. 1, will cause the release member 46, attached thereto, to move to the left and force the tapered surfaces 54a—54b and 54c—54d under the rollers associated therewith in such manner as to wedge the shafts 32 and 33 outwardly from the electrode 15, thereby disengaging the feeding wheels 26 and 27 from said electrode. 50

In order that the sleeve 45 may be moved to the left whenever it is desired to release the electrode 15 by disengaging the feeding wheels 26 and 27, I provide thereon a collar 60 which may be suitably attached thereto as by screw threads 61. The collar 60 may of course be adjusted longitudinally of the sleeve 45 by screwing it to the right or left along the screw threads 61. 60

I provide a lock nut 62 which may be jambed against the collar 60 in order to hold it in the desired location. The collar 60 is best shown in Fig. 5 as including an annular recess 63 formed by a pair of radial flanges 64 and 65. The collar 60 is adapted to be shifted to the right or left 70 by a cam 66 which extends into the annular recess 63 and is arranged to engage either of the flanges 64 or 65. 70

The cam 66 is carried on a cam shaft 67 which preferably extends upwardly and is rotatably 75

supported in a bracket member 68 positioned externally of the housing 16 and suitably secured thereto. The means for rotatably supporting the cam shaft 67 preferably comprises a suitable anti-friction roller bearing 69 interposed between the cam shaft 67 and the bracket 68 and retained therebetween by means of a collar 70 suitably attached to the cam shaft 67 as by means of a set screw 70a. It is to be understood that

5 I comprehend the substitution of other types of anti-friction bearings, as for example a ball bearing, for the type of bearing shown. The cam shaft 67 terminates at its upper end in a suitable lever or handle 71 which may be rotated so as 10 to move the cam 66 from the dotted line position as shown in Fig. 5 in a clockwise direction to the solid line position shown.

15 In order to limit the travel of the handle 71 between the two aforementioned positions, I provide stops 72 and 73 suitably attached as by means of screw threads 74 to the bracket 68 and so positioned that the handle 71 will rotate the cam shaft 67 through less than 180 degrees when being moved from the stop 72 to the stop 73.

20 I prefer to make the cam 66 in the form of an eccentric of circular cross section and of such diameter that it will substantially fill the width of the annular recess 68 so that rotation of the cam shaft 67 by means of the handle 71 in 25 either direction will cause a corresponding movement of the collar 68. The relative positions assumed by the various previously described parts upon operation of the handle 71 to release the electrode from the electrode feeding wheels 26 and 27 is illustrated in Fig. 3.

25 Briefly summarizing, it will be seen that manual rotation of the handle 71 from the position shown in Fig. 1 to the position shown in Fig. 3 operates to move the collar 68 and the slideable sleeve 45 adapted thereto to the left against the force of the tension springs 36 and 37, thereby forcing the release member 46 into engagement with the rollers 55a, 55b, etc. so as to overcome the force of the tension springs 36 and 37 and disengage the electrode feeding wheels 26 and 27 from the electrode 15 to free said electrode therefrom and permit easy removal of the electrode from the lamp mechanism.

30 A reverse rotation of the handle 71, in other words, from the position shown in Fig. 3 to the position illustrated in Fig. 1, will move the slideable sleeve 45 in the opposite direction and disengage the release member 46 from the feeding wheels 26 and 27 so as to allow the tension springs 36 and 37 to force said feeding wheels into engagement with the electrode 15.

35 By locating the cam 66 on its shaft such that the electrode rotating and feeding mechanism is put into operation so as to rotate the electrode in the normal operation of the lamp (such direction being indicated by the arrow 38) the direction in which the friction forces exerted between the flange 64 and the periphery of the cam 66 will be such as to tend to rotate the cam 66 and its shaft 67 in a direction tending to disengage the release mechanism and cause re-engagement of the feeding mechanism.

40 I prefer to limit the movement of the cam 66 to the range previously defined so that the direction of the rotation tending to be produced in the manner previously described will be limited to the counterclockwise direction as viewed in Fig. 5 so as to tend to disengage the release mechanism. In order that this tendency to cause 45 rotation of the cam 66 may actually effect a

rotation thereof, I have provided the previously described anti-frictional force tending to rotate the cam shaft 67 will be greater than, and hence will overcome, the frictional forces in the bearing 69 tending to cause the cam shaft 67 to remain at rest.

5 It will therefore be observed that, should the handle 71 be left in the released position as illustrated in Fig. 3, after the insertion of a new electrode 15, placing the lamp mechanism in operation will impart a rotary motion to the cam shaft 67 in the manner previously described. As soon as the cam 66 has rotated from the dead center position illustrated in Figs. 3 and 5, the force tending to urge the sleeve 45 forwardly, due to the interaction of the springs 36 and 37 through the rollers and the release member 46, will cause the cam 66 to continue to rotate and allow the sleeve 45 to move to its forwardmost position, as illustrated in Fig. 1, so as to re-engage the electrode feeding mechanism with the electrode.

10 I have found that the provision of an anti-friction type bearing for rotatably supporting the cam shaft 67 is very important, in that the automatic operation just described is not possible if an ordinary bearing is used, since the frictional forces arising therein and tending to hold the cam shaft stationary are too large to be overcome by the frictional engagement between 15 the cam 66 and the flange 64.

15 The electrode release mechanism of my invention is therefore constructed in such a manner and provided with such a control mechanism that it is impossible for an operator of a lamp 20 equipped with this device to inadvertently operate the lamp without the feeding mechanism functioning. This is due to the fact that, as hereinbefore described, resumption of the operation of the lamp after installation of a new electrode will automatically cause the electrode release mechanism to be disengaged from the feeding mechanism and will permit re-engagement of the feeding wheels with the electrode.

25 In Figs. 11, 12 and 13 I have illustrated an alternative control means for withdrawing the sleeve 45 for the purpose of releasing the electrode from the electrode feeding mechanism and which is claimed in my divisional application Serial No. 257,276, filed February 20, 1939. Reference to Fig. 11 will disclose that in this form of the invention I prefer to employ a slideable sleeve 45a which extends rearwardly a sufficient distance to extend beyond the edge of the previously mentioned bevel gear 18 to provide clearance between said gear and a collar 78 which is attached to the slideable sleeve 45a. The collar 78 may be adjustably attached to the sleeve 45a as by means of screw threads 79 and locked in whatever position is desired by means of a lock 80 nut 80. The collar 78 includes a cylindrical portion 81 and a flange portion 82 of a diameter larger than the cylindrical portion 81 and located rearwardly with respect thereto.

30 A handle mechanism 83 is provided which includes a handle 84 adapted to be used by an operator in releasing the electrode 15 from the electrode feeding mechanism and a plate portion 85 formed integrally with the handle 84. The plate portion 85 is provided with a central opening 86 35 adapted to slide over the cylindrical portion 81 of the collar 78 and provided with three substantially equally spaced holes 87, 88 and 89 of such diameter as to loosely accommodate steel balls 80, 81 and 82. The holes 87, 88 and 89 are 40

spaced from the center of the sleeve 45a a distance such that the balls included therein may rest upon the cylindrical portion 81 of the collar 18.

5 A retainer 93 is suitably attached to the plate portion 85 of the handle mechanism 83 and cooperates with the flange portion 82 of the collar 18 to confine the lowermost steel balls 91 and 92. This complete mechanism is enclosed in a casing 94 which is attached to the housing 16 as by 10 screws 95, and which provides an inwardly projecting rib 96. The rib 96 may be of trapezoidal cross section, providing an essentially radial surface 97 adjacent the upper steel ball 90 and a sloping surface 98 for providing strength and 15 rigidity to the member 96.

10 As best illustrated in Figs. 11 and 13, the radial surface 97 is semi-helical in shape so as to provide a maximum clearance between said surface and the flange 82 at the right hand end of 20 the flange 82 as viewed in Fig. 12 and a minimum clearance therebetween at the left hand end. The radial surface 97 cooperates with the flange 82 to confine the upper ball 90 therebetween. A 25 suitable slot 99 is provided in the housing 94 to allow the handle 84 to extend therethrough.

15 It will be seen that rotation of the handle mechanism 84 to the left or counterclockwise, as viewed in Fig. 12, will cause the balls confined 30 therein to rotate with the handle assembly. As the upper ball 90 moves between the flange 82 and the helical surface 97 of the projection 96 the space therebetween for said ball becomes progressively smaller so that a wedging action is developed to force the collar 18 and the sleeve 45a attached thereto to the left, as viewed in Fig. 11.

25 The sleeve 45a is coupled to the electrode feeding mechanism in the same manner as described relative to the sleeve 45. Hence, movement of the 30 slideable sleeve 45a to the left will release the feeding mechanism from the electrode 15 in a manner identical to that previously described in connection with the sleeve 45.

35 Conversely, a movement of the handle 84 to the right after the sleeve 45a has been moved to the electrode releasing position will move the upper ball 90 into that portion of the space between the flange 82 and the radial surface 97 which provides the greatest space therebetween. As previously shown, the interaction between the 40 springs 36 and 37 and the other mechanisms forming the electrode releasing device continuously urges the slideable sleeve 45a forwardly so that as soon as the handle 84 is moved to the 45 right the slideable sleeve 45a will move forwardly in correspondence therewith so as to place the electrode feeding mechanism into operative engagement with the electrode 15.

50 This form of control mechanism is also automatically releasable and is responsive to rotation 55 of the electrode 15 to effect this release. Whenever the electrode 15 and the slideable sleeve 45a associated therewith is rotated in the direction of the arrow 38, the flange 82 of the collar 18 will be rotated therewith. Inasmuch as the ball 90 is 60 confined between the flange 82 and the helical rib 96, rotation of the flange 82 will roll the ball between said flange and said rib toward the open end of the space therebetween. This allows the 65 sleeve 45a to slide forwardly to engage the electrode feeding wheels 26 and 27 in a manner previously described.

70 Other modifications of the electrode releasing mechanism include a construction which is illustrated in Figs. 6 and 7 and claimed in my divi- 75

70 sional application Serial No. 257,276. Reference to Fig. 6 reveals that in this form of the invention a modification of the release member 46 dispenses with the wedging surfaces 54a, 54b, etc. so as to provide a release member 46a upon which rollers 105, 106, 107 and 108 are pivotally mounted on longitudinal portions 52a and 53a by means of studs 109, 110, 111, and 112. Each of the studs is provided with an upset head for retaining the roller associated therewith.

10 It will also be noted that the rollers previously described as being rotatably mounted upon the shafts 32 and 33 have been removed and in their place an enlarged portion 113 has been substituted. It is readily seen that movement of the 15 sliding sleeve 45 to the left through operation of either of the control mechanisms previously described will cause the rollers 106, 107, 108 and 109 to engage the corresponding enlarged portions 113 of the shafts 32 and 33 in a wedging 20 manner so as to disengage the electrode feeding wheels 26 and 27 from the electrode 15.

25 Figs. 8 and 9 illustrate a modification of the electrode release device of my invention in which the release member 46 is simplified so as to provide a release member 46b which includes only a transverse portion 50a similar to the previously mentioned transverse portion 50 of member 46. In this form of my invention I prefer to employ a system of bell cranks 115 which includes bell 30 cranks 116, 117, 118 and 119.

35 The bell cranks 115 may be pivotally mounted upon suitable projections 120 formed on the bearing brackets 30 and 31 and provided with suitable holes 121 for encircling the protruding ends of 35 the shafts 32 and 33. The lever arm portions of the bell cranks 115 are arranged to be engaged by the transverse portion 50a of the release member 46b which extends in overlapping relation relative to the bell cranks 115.

40 Reference to Fig. 8 will indicate that movement of the slideable sleeve 45 to the left for the purpose of releasing the electrode 15 will cause those portions of the bell cranks 115 which are engaged by the release member 46b to be moved 45 to the left therewith. This movement will cause the portion of the bell cranks 115 which engage the shafts 32 and 33 to be moved outwardly away from the electrode 15, thereby effecting the 50 previously described release. It will be noted that in this form of the invention the bell cranks are pivoted at the angle portions thereof with either end moving to effect the release of the electrode.

55 In Fig. 10 I have illustrated an alternative arrangement of the bell cranks 115 which is claimed in my divisional application Serial No. 257,276. In this modification one end of the bell crank is pivotally mounted to the bearing brackets 30 and 31 while the angle portion encircles the shafts 32 and 33 whereupon movement of the ends of the bell crank 115 engaged with the release member 46b will cause the shafts 32 and 33 to move outwardly with respect to the electrode 15 and effect the release thereof in the manner previously set 60 forth. In this form of the invention it should be noted that the point of engagement between the lever arm portions of the bell cranks 115 with the release member 46b lies substantially on a line between the shafts 32 and 33. Comparison 65 of Figs. 8 and 10 reveals that this latter arrangement is more compact and less likely to interfere with the shield 40.

70 It will be noted that I have provided a release device in which the restoring force tending to 75

restore the feeding mechanism to an electrode engaging position increases as the device is operated in a direction to release the electrodes. In other words, whenever the slideable sleeve 45 is moved to the left to effect the release of the electrode 18, said release is accomplished by overcoming the force of the tension springs 36 and 37. The force exerted by these springs necessarily appears during a release operation as a force tending to restore the slideable sleeve 45 to a non-released position.

Inasmuch as the mechanical advantage provided between the sleeve 45 and the springs 36 and 37 is of the constant ratio type, and inasmuch as the force exerted by the springs increases as the springs are stretched during the release operation, it follows that the force tending to restore the sleeve 45 to the non-released position must increase as the sleeve is moved toward the released position.

This differs from the present construction in that the mechanical advantage provided between the sleeve and the springs increases in those in present use as the sleeve is moved to a released position. This increase in mechanical advantage overcomes the increased force from the springs with the result that the restoring force on the sleeve becomes less and less as the sleeve is moved toward the released position. It will be seen, in summary, that the device of my invention eliminates a major disadvantage in the present construction in that those in present use, in which the restoring force reduces as the feeding mechanism is released, tend to allow the feeding mechanisms to become locked in the disengaged position, thereby requiring repairs to said mechanisms and a consequent loss of time and money.

It will also be seen that I have provided a release mechanism for electrodes employed in an arc lamp which is provided with a control means located externally of the lamp mechanism and in which operation of said control means may be directed to either release the electrode for replacement or engage the feeding means with a new electrode.

I claim:

1. In combination with an arc lamp having an electrode carrier rotatable about its longitudinal axis and feed wheels for feeding an electrode carried by said carrier in the direction of said axis: a means mounting said feed wheels for movement toward and away from said electrode; and control means manually operable to move said feed wheels away from said electrode and automatically operable responsive to rotation of said electrode carrier for moving said feed wheels toward said electrode.

2. In an arc lamp, the combination of: a rotatable electrode carrier for supporting an electrode for rotation about its longitudinal axis; means for rotating said carrier; electrode feeding wheels for engaging said electrode; mounting means for mounting said feeding wheels on said carrier for movement out of engagement with said electrode and into electrode engaging position; a release member engageable with said mounting means for moving said feeding wheels out of engagement with said electrode; and a control means coupled to said release member and responsive to a manual operation for moving said feeding wheels out of engagement with said electrode and responsive to rotation of said electrode carrier for moving said feeding wheels to an electrode engaging position.

3. In an arc lamp, the combination of: a rotatable electrode carrier for supporting an electrode for rotation about its longitudinal axis; means for rotating said carrier; electrode feeding wheels for engaging said electrode; mounting means for mounting said feeding wheels on said carrier for movement out of engagement with said electrode and into electrode engaging position; a release member engageable with said mounting means for moving said feeding wheels out of engagement with said electrode; and a control means coupled to said release member and responsive to a manual operation for moving said feeding wheels out of engagement with said electrode and responsive to rotation of said electrode carrier for moving said feeding wheels to an electrode engaging position, including a sliding sleeve interposed between said electrode and said carrier for rotation therewith and for operating said release member, a flange on said sleeve, and manually operable means engaging said flange for sliding said sleeve, said means being responsive to rotation of said flange to operate said release member to move said feeding wheels to electrode engaging position.

4. In an arc lamp, the combination of: a rotatable electrode carrier for supporting an electrode for rotation about its longitudinal axis; means for rotating said carrier; electrode feeding wheels for engaging said electrode; mounting means for mounting said feeding wheels on said carrier for movement out of engagement with said electrode and into electrode engaging position; a release member engageable with said mounting means for moving said feeding wheels out of engagement with said electrode; a sliding sleeve interposed between said electrode and said carrier for rotation therewith and for operating said release member; an annular recess on said sleeve; and an eccentrically mounted member engaging both sides of said recess whereby rotation of said member slides said sleeve to release or engage as desired said electrode from said feeding wheels.

5. In an arc lamp having means for rotating an electrode about its longitudinal axis, the combination of: a plurality of feed wheels for engaging and feeding said electrode in the direction of said axis; shafts for rotatably supporting said feed wheels; means coupling said feed wheels to said electrode rotating means; a face plate mounting said shafts for movement toward each other to engage an electrode between said wheels and for movement away from each other to disengage said wheels from said electrode; a plurality of rollers rotatably and slideably supported by said shafts; a plurality of grooves in said face plate for engaging the sides of said rollers to prevent sliding movement thereof on said shafts; wedge means having inclined surfaces interposed between the shafts of adjacent wheels and engageable with the rollers thereon for moving said shafts away from each other to disengage said wheels from said electrode; and means for engaging said wedge means with said rollers.

6. In a holder for supporting an electrode, the combination of: a plurality of rotatable feeding wheels; axles mounting said feeding wheels for rotation; means mounting said axles for movement toward and away from said electrode; resilient means for urging said feeding wheels into engagement with said electrode; rollers mounted on said axles; movable wedge means having inclined surfaces interposed between the rollers associated with adjacent feeding wheels for engaging said rollers to force said feeding wheels out

of engagement with said electrode; and means for moving said wedge means.

7. In a holder for supporting an electrode, the combination of: a plurality of rotatable feeding wheels; axles mounting said feeding wheels for rotation; means mounting said axles for movement toward and away from said electrode; resilient means for urging said feeding wheels into engagement with said electrode; a plurality of bell cranks, each including a pivot point, an arm adjacent said pivot point engaging one of said axles, and a lever portion adjacent said arm; stationary pivot means engaging said pivot points; a movable release member engageable with each of said lever portions; and means for moving said release member into engagement with said lever portions whereby said bell cranks rotate about said pivot points and force said feeding wheels out of engagement with said electrode.

8. In an electrode holder, the combination of: a rotatable electrode carrier; an electrode carried by said carrier; a plurality of rotatable feeding wheels; axles mounting said feeding wheels for rotation; means mounting said axles on said carrier for movement toward and away from said electrode; resilient means for urging said feeding wheels into engagement with said electrode; rollers mounted on said axles; movable wedge means interposed between the rollers associated with adjacent feeding wheels for engaging said rollers to force said feeding wheels out of engagement with said electrode; and a control means coupled to said movable wedge means and responsive to a manual operation for moving said feeding wheels out of engagement with said electrode carrier and responsive to rotation of said electrode carrier for moving said wedge means out of engagement with said rollers to allow said resilient means to move said feeding wheels into an electrode engaging position.

9. In an electrode holder, the combination of: a rotatable electrode carrier; an electrode carried by said carrier; a plurality of rotatable feeding wheels; axles mounting said feeding wheels for rotation; means mounting said axles on said carrier for movement toward and away from said electrode; resilient means for urging said feeding wheels into engagement with said electrode; a plurality of bell cranks, each including a pivot point, an arm adjacent said pivot point engaging one of said axles, and a lever portion adjacent said arm; stationary pivot means engaging said pivot points; a movable release member engageable with said lever portions, whereby movement of said release member rotates said bell cranks about said pivot points and forces said feeding wheels out of engagement with said electrode; and a control means for moving said release member responsive to a manual operation for moving said feeding wheels out of engagement with said electrode and responsive to rotation of said electrode carrier for moving said release member out of engagement with said lever portions to allow said resilient means to move said feeding wheels into an electrode engaging position.

10. In an arc lamp, the combination of: an electrode; a rotatable electrode carrier supporting said electrode for rotation about its longitudinal axis; electrode feeding wheels for engaging said electrode; mounting means for mounting said feeding wheels on said carrier for

movement out of engagement with said electrode and into electrode engaging position; a release member engageable with said mounting means for moving said feeding wheels out of engagement with said electrode; a slidable member coupled to said release member and carried by said electrode carrier so as to be rotatable therewith; a flange portion secured to said slidable member; a cam member mounted for eccentric rotation to engage said flange member; and manually operable means for rotating said cam member in a direction opposite to the direction of rotation of said flange to slide said slidable member and disengage said feeding wheels from said electrode, whereby rotation of said electrode carrier causes a reverse rotation of said cam member to move said feeding wheels into electrode engaging position.

11. In an arc lamp, the combination of: an electrode; a rotatable electrode carrier supporting said electrode for rotation about its longitudinal axis; electrode feeding wheels for engaging said electrode; mounting means for mounting said feeding wheels on said carrier for movement out of engagement with said electrode and into electrode engaging position; a release member engageable with said mounting means for moving said feeding wheels out of engagement with said electrode; a slidable member coupled to said release member and carried by said electrode carrier so as to be rotatable therewith; a flange portion secured to said slidable member; a cam member mounted for eccentric rotation to engage said flange member; manually operable means for rotating said cam member to move said slidable member and disengage said feeding wheels from said electrode; and means limiting the rotational movement of said cam member to a distance such that said cam member is prevented from passing a dead-center position relative to said flange, whereby rotation of said flange will rotate said cam member in the reverse direction and move said feeding wheels to electrode engaging position.

12. In an arc lamp, the combination of: an electrode; a rotatable electrode carrier supporting said electrode for rotation about its longitudinal axis; electrode feeding wheels for engaging said electrode; mounting means for mounting said feeding wheels on said carrier for movement out of engagement with said electrode and into electrode engaging position; a release member engageable with said mounting means for moving said feeding wheels out of engagement with said electrode; a slidable member coupled to said release member and carried by said electrode carrier so as to be rotatable therewith; a flange portion secured to said slidable member; a cam member frictionally engaging said flange; means eccentrically mounting said cam member for rotation such that the frictional resistance to said rotation is less than the frictional engagement between said cam and said flange; and manually operable means for rotating said cam member in a direction opposite to the direction of rotation of said flange to slide said slidable member and disengage said feeding wheels from said electrode, whereby rotation of said electrode carrier causes a reverse rotation of said cam member to re-engage said electrode feeding wheels with said electrode.
